STRAIGHT HOLE DRILL COLLAR

Leonard E. Stewart, Midland, and Marvin J. Winters, Odessa, Tex., assignors to Noble Drilling Corporation, Tulsa, Okla., a corporation of Delaware

Application September 10, 1949, Serial No. 115,066

4 Claims. (Cl. 255—27)

1

This invention relates to oil well drilling equipment.

In drilling oil well holes with conventional equipment, such as that in use prior to the present invention, the use of heavy weight on the cutting tool is relied upon to achieve the desired speed of drilling. However, when the cutter enters a sloping formation which is very hard, such for example as chert, it tends immediately to drift and this tendency must at once be checked.

Heretofore the only effective means in use to check drifting of the cutting tool, under these conditions, has been to reduce to a large extent the weight resting on the cutter, usually by applying upward tension on the drill pipe sufficient to offset part or most of the weight of the drill collar. This, in turn, reduces the speed of cutting and, when the chert or other hard formation is very thick, may extend for many hours or days the length of time needed to drill a hole to the producing formation.

A drill collar according to the present invention is capable of cutting under full weight, and at full speed, through hard and sloping formations, such as chert, of great thickness, without appreciable or excessive drift, and thereby to enable holes to be drilled through such formations in a materially shorter number of hours or days than has heretofore been considered possible.

In the drawings annexed hereto—

Fig. 1 is a vertical section through a well drilling in a hard rock formation, illustrating an arrangement embodying the invention;

Fig. 2 is a fragmentary vertical elevation of the improved drilling equipment;

Figs. 3 and 4 are transverse sections taken respectively along lines 3—3 and 4—4 of Fig. 2, each being viewed in the direction of the arrows;

Fig. 5 is an enlarged partial longitudinal section taken along line 5—5 of Fig. 1 being in part broken away; and,

Fig. 6 is a transverse section taken along line 6—6 of Fig. 5.

Referring to the drawing, 10 denotes a well hole that is being drilled in hard rock formation, for example, chert 11 by a drill bit 12 which is rotated by means of a drill collar. This collar has a portion 13 in which the drill bit is secured. A portion 14 of the drill collar of somewhat larger diameter than portion 13 adjoins the latter and is provided in its face with longitudinal recesses 15 in which conventional reamers 16 are removably positioned. Preferably these reamers 16 are so dimensioned that the maximum reaming di-

2

ameter is substantially equal to the outside diameter of the bit 12 when new. A circumferential fixed abutment portion 14a of the drill collar adjacent the portion 14 has a larger diameter than portion 14 but less than the outside diameter of bit 12. An intermediate or sleeve-receiving portion 17 of the drill collar adjoins the fixed abutment portion 14a, being less in diameter than said portion 14a and defining a shoulder 18 therewith.

A substantially cylindrical sleeve 19 is slidably and rotatively borne on the intermediate portion 17 of the drill collar. This sleeve has substantial length being of the order of 8 to 20 feet. The outside diameter of sleeve 19 is smaller by a small percentage than that of a fresh bit 12. By way of example only, if the outside diameter of a fresh bit 12 is 8½ inches, the outside diameter of sleeve 19 is approximately 8⅓ inches. The opposite ends of sleeve 19 taper inwardly. Several shallow grooves 20 extend parallelly and longitudinally in the outer surface of sleeve 19. In the embodiment shown, six grooves 20 spaced apart equally at approximately 60° from each other are provided. The peripheral surfaces 21 between each two adjacent grooves is approximately 50° in width so as to present an extensive cylindrical outer surface interrupted only by the grooves which comprise a minor portion of the total cylindrical surface. The inner diameter of sleeve 19 is somewhat larger than the outer diameter of portion 17 on which it is longitudinally slidable. A plurality of equi-spaced openings or holes 22 extend through the wall of sleeve 19 providing communication between its outer and inner surfaces to permit a flow of fluid for cleaning purposes as will be described.

The intermediate portion 17 of the drill collar is threaded externally at 24 and extended beyond the threaded portion is a portion 25 of slightly reduced diameter. A threaded nipple 26 is provided on the end of portion 25 for attachment of the lowest drill pipe. An internally threaded retaining collar or locking nut 27 freely slidable on portion 25 is screwed onto the threads 24 providing an upper stop or shoulder 27a for the sleeve 19. This shoulder 27a is spaced apart from the shoulder 18 a distance sufficiently in excess of the length of sleeve 19 to provide approximately a two foot longitudinal travel slide of the sleeve 19 on portion 17, for purposes presently to be described.

The retaining collar 27 is suitably locked in its position on the threaded portion 24, for example, by the transversely extending keys 29 and

locking pins 30. Any other conventional locking arrangement may be provided.

Operation

The operation and advantages of the improved construction are as follows:

Wash water or circulation fluid is fed downwardly through the drill pipe and the collar to an outlet adjacent the bit 12. During normal drilling operations, the drill pipe rotates the bit and the cuttings are washed upwardly by the wash water flow around the outside of collar portion 13, upwardly through the spaces between the reamers 16, and upwardly through the passages defined by grooves 20 of sleeve 19 and the walls of well 10. Some of the wash water enters the holes 22 flowing in the clearance between the inside diameter of sleeve 19 and outer diameter of pipe portion 17 to wash out any clogging matter. All drilling cuttings eventually are washed out of the mouth of the well. The reamers 16, which are relatively close to the bit and which wear out much more slowly than the bit 12 itself, maintain the desired well diameter notwithstanding reduction of the bit diameter at a more rapid rate as a result of wear in the drilling operation. The sleeve 19 is spaced approximately 4 feet from the top of the bit 12. If, due to a hard sloping formation, the bit tends to drift, this tendency is counteracted by the sleeve 19 whose smooth cylindrical surfaces 21 bear against the well wall and guide the bit in a straight path without, however, preventing rotation of the drill collar 14, 17 and the bit 12. The sleeve 19 then functions as a vertical guide for the drill collar and the bit 12 and either prevents drift entirely or reduces it to an inconsequential amount. Inasmuch as the reaming diameter of the reamers 16 maintain the required well diameter, and this is slightly larger than the diameter of the cylindrical surfaces of the sleeve, the lower end of sleeve 19 will ordinarily follow fairly close to the bit because the cylindrical surfaces of sleeve 19 are slightly smaller than the well diameter.

Under ordinary conditions, as for example in soft formation where there is less tendency to drift, the cutters 12 may be placed under very heavy weight and drilling will proceed at a rapid rate. In all drilling, it is noted that cutters such as 12 tend to wear down rapidly, and as they become worn they cut a hole of less than desired size. On the other hand, reamers 16 maintain their size for a much longer period of time, often lasting as long as three cutters. In soft formations the sleeve 19, being slightly smaller in outside diameter than the reamers 16, slides freely in the hole and rests against the lower stop 18.

When our drill strikes a very hard and sloping formation, tending to cause the cutters to drift, the upper end of sleeve 19 comes in contact with the internal wall of the hole and, by reason of its length, serves as a guide to hold the cutters 12 in a straight path. In performing this function, the very slight clearance between the outer cylindrical surface of sleeve 19 and the internal wall of the hole, and the fact that the major portion of the outer surface of sleeve 19 is of a smooth cylindrical form, enables the drill as a whole to be kept under heavy weight and to continue cutting without loss of speed other than the slowing-up due to the harder stone being drilled. We have found that full weight can be maintained on our drill while passing through sloping chert, and that the drill will go through the chert without prohibitive drifting.

A further advantage of the smooth cylindrical outer surface of sleeve 19 is that it has a minimum tendency to become wedged or stuck in the hole. In order to facilitate loosening of the sleeve, if this happens, we provide a substantial clearance between each end of sleeve 19 and the abutments 18 and 21a aggregating, in the example here shown, about two feet. If the sleeve becomes wedged or stuck, we continue drilling until abutment 21a comes in contact with the upper end of sleeve 19. Then the drill collar as a whole is hauled rapidly upward at increasing speed till abutment 18 strikes the lower end of sleeve 19. For this purpose we prefer a free movement of about two feet, which is sufficient to enable the drill collar to be moving upward, at the moment of contact, with sufficient momentum to free sleeve 19 from any frictional contact with the hole likely to be encountered in practice. When it becomes necessary to free sleeve 19 in the manner just described, the fact of its substantial length, plus the fact that it possesses an outer surface of which a major part is smooth and cylindrical, prevents the sleeve from locking or digging itself into the wall of the hole, and enables it to be readily freed even in the hardest formations.

The following is by way of example, in order to illustrate our invention. We have drilled a hole of $8\frac{3}{4}$ " diameter with a drill as herein described to a depth of several thousand feet. The drill collar assembly was of sufficient weight to permit about 80,000 pounds to be placed upon the cutters and at no time was this weight reduced. This drill maintained an average speed of drilling of about 20 feet per hour through a series of formations including a deep bed of chert, with an average drift not exceeding $\frac{1}{2}$ degree. A conventional drill, of the kind heretofore in use, operating side-by-side with the drill above mentioned and passing through the same formations, on encountering the chert had to be lightened till the weight on the cutters was reduced to about 10,000 pounds, and it then cut at the rate of only about 3 to 4 feet per hour. Even with this reduction in weight and speed, the conventional drill drifted an average of nearly 7 degrees in reaching the same depth.

While a specific embodiment of the invention has been described, variations in structural detail within the scope of the claims is possible and is contemplated. There is no intention, therefore, of limitation to the exact details shown and described.

What is claimed is:

1. A drill collar having three adjacent portions of different outside diameters, the first portion being adjacent one end of the collar, a second portion intermediate the length of the collar and of larger outside diameter than the first-mentioned portion, and a third portion adjacent the other end of the collar and being of larger outside diameter than the second-mentioned portion and separated therefrom by a fixed circumferential abutment, screw threads in that end of the intermediate portion which is adjacent the first-mentioned portion, a locking nut adapted to be freely slidable upon the first-mentioned portion and to engage the threads of the intermediate portion, a sleeve slidable upon said intermediate portion and adapted to be moved longitudinally thereof in a path of travel determined by the engagement of its ends with said abutment and said nut respectively, and reamer

cutters mounted upon said third-mentioned portion defining a radius of action slightly larger than the radius of said sleeve.

2. A drill collar as specified in claim 1, wherein the sleeve has a plurality of shallow longitudinal grooves extending the entire length of its outer cylindrical surface, the said grooves being separated from one another by smooth curved surfaces constituting longitudinal segments of a cylindrical surface, the said smooth curved surfaces constituting the major part of the area of the entire outer cylindrical surface of said sleeve.

3. A drill collar as specified in claim 1, wherein the sleeve has a plurality of shallow longitudinal grooves extending the entire length of its outer cylindrical surface, the said grooves being separated from one another by smooth curved surfaces constituting longitudinal segments of a cylindrical surface, the said smooth surfaces constituting about $\frac{5}{6}$ of the area of the entire outer cylindrical surface of said sleeve.

4. A drill collar as specified in claim 1, wherein the sleeve has a plurality of shallow longitudinal

grooves extending the entire length of its outer cylindrical surface, the said grooves being separated from one another by smooth curved surfaces constituting longitudinal segments of a cylindrical surface, the said smooth surfaces constituting the major part of the area of the entire outer cylindrical surface of said sleeve, and an open drilling penetrating the sleeve from its outer to its inner surfaces positioned in at least one of 10 said grooves.
